UNITED STATES PATENT OFFICE.

ABRAHAM T. WILLIAMSON, OF RINGOES, NEW JERSEY, EXECUTOR OF
JACOB W. WILLIAMSON, DECEASED.

IMPROVEMENT IN LOCKING-LATCHES.

Specification forming part of Letters Patent No. **157,257**, dated November 24, 1874; application filed
October 10, 1874.

To all whom it may concern:

Be it known that JACOB W. WILLIAMSON, late of Ringoes, deceased, in the county of Hunterdon and State of New Jersey, did invent certain new and useful Improvements in Locks; and I do hereby declare the following to be a full, clear, and exact description of the invention, such as will enable others skilled in the art to which it pertains to make and use it, reference being had to the accompanying drawings, which form part of this specification, in which—

Figure 1 is a perspective view of lock complete. Figs. 2, 3, and 4 are details.

This invention has relation to a combined door lock and latch; and it consists in the novel construction and combination of a pivoted latch, tumbler-arm, key-slide, and eye-plate, whereby the locking and unlocking of the latch can only be effected by peculiar manipulation of the key, as hereinafter specifically set forth.

Referring to the accompanying drawings, A designates the lock-case, and B the latch. The latter is of a very peculiar shape, and comprises two principal parts—the arm *a* and bar *b*, lying, respectively, lengthwise and crosswise of the case. The upper end of the bar *b* is formed with an eye, *c*, through which passes a pin, pivoting the latch to the case in one of the upper corners. The said bar bears the beveled latch-projection *d*, which plays through a suitable opening in the end of the case. D is a cam attached to the knob-shaft and located within a recess, E, formed in the rear end of the latch-arm *a*. When the knob is turned either to the right or left the arm *a* is raised by the pressure of the cam-wings or facets *e¹* *e²* against the curved surfaces *e³* *e⁴* of the arm, and the latch turned upon its pivot so as to withdraw the beveled projection *d*. The latch can only be moved, however, when released from the locking mechanism, to be presently described. When the cam assumes the position shown in Fig. 1, which it will of its own weight, or of the weight of a suitable pendent knob, the arm *a* will fall automatically, so as to throw outward the projection *d*. In closing the door, the latch is operated through the pressure of the part *d* against the

keeper. Of the mechanism for locking, E' designates a curved arm, pivoted to the case at its upper end, and slotted in the direction of its length at F. Through the slot F the arm *a* of the latch passes, and plays freely, said arm being recessed at *a²* for such purpose. F' are prongs projecting from the lower end of the arm E', so as to embrace between them and within the slot F the recessed portion of the latch-bar *b*, located behind the projection *d*, and lettered *d'*. G designates a slotted slide, resting upon the bottom of the lock-case, and guided by means of a stop-pin, *g*, and bevel projections *g¹* *g²*, attached rigidly to the case. Upon its upper portion, said slide has a transverse semicircular recess, *h*, and on its lower edge a longitudinal beveled groove, *h¹*, and transverse beveled groove *h²*. I is a plate arranged across the recess *h*, and constructed with a central eye, *i*, and one or more concentric wards, *i'*, forming segmental channels *i''*. The forward end of the slide is tenoned so as to enter the slot F of the bar E' behind the prongs F'. At the base of said slide notches or rabbets *j* are made for the reception of projections *j'*, formed by channeling the slide at the sides and base of the tenoned end, as shown. K designates the key-hole, and K' the key.

The operation of the locking mechanism is as follows: The slide being in such a position that the eye *i* shall be on the opposite side of the key-hole from the bar E', the key is inserted with the shank below the bit, and is then turned toward the eye *i*, and the projection *k* inserted in the latter. The key is then turned in the opposite direction, thereby lifting the slide above the blocks *g¹* *g²*, and conveying it forward until the groove *h²* and block *g²* coincide, when it is lowered upon the bottom of the case. As the slide moves, it forces the arm E' in front of it, causing the prongs F' *F'* to enter the recesses *d'*. After the slide descends, its end, touching the bar *b*, acts a stop, preventing the latch from being moved back by external appliances. Upon the descent of the slide, the arm E being released, recedes, until its lower end lies in the recess *h*, and the lugs or stops *k'* on the ends of the prongs touch the slide, as shown. The

blocks $g^1 g^2$ occupying, when the latch is locked, respectively the notches $h^3 h^2$, prevent the slide from being pushed back unless it is first lifted. The object of the arm E' is to prevent the required raising of the slide, except upon the insertion and proper manipulation of the key. To unlock the latch, assuming the parts to be in the position shown in the drawing, the key is inserted and first turned toward the eye i , (which is now guarded by the arm E'), so as to raise said arm and admit the projection k to said eye. The key is then turned in the opposite direction, whereupon the slide is lifted and moved back, so as to leave the latch free.

The advantages of the lock, as described, are so obvious as to require no discussion.

I claim—

The combination of the latch B , tumbler-arm E , slide G , and eye-plate I , substantially as described, and for the purpose specified.

In testimony that I claim the foregoing I have hereunto set my hand this 11th day of September, 1874.

ABRAHAM T. WILLIAMSON,
Executor of Jacob Williamson, deceased.
